United States Patent Office.

JACOB S. SIMMERMAN, OF MILLVILLE, NEW JERSEY.

Design No. 2,621, dated April 16, 1867.

DESIGN FOR A STOVE HANDLE.

The Schedule referred to in these Letters Patent and making part of the same.

TO ALL WHOM IT MAY CONCERN:

Be it known that I, JACOB S. SIMMERMAN, of Millville, county of Cumberland, and State of New Jersey, have originated a new Design for the Handles of Stoves and Furnaces, of which the following is a full, clear, and exact description of the same, reference being had to the accompanying drawings, which form a part of this specification.

A is a metal rod which is bent into the form of a coil or spiral, the inner end of the holder being secured to a door by means of a screw-thread, as fully seen in the drawings. A slight taper is given from the inner to the outer end of the holder.

What I claim, and desire to secure by Letters Patent, is—

The design for stove-door handles, as shown and described.

In testimony whereof I set my signature in presence of two witnesses.

Witnesses:

Wm. L. NEWELL,
R. S. IRELAND.

J. S. SIMMERMAN.
